CLAIM

The ornamental design for a rear door for an automobile, as shown and described.

DESCRIPTION

FIG. 1 is a right front, perspective view of a rear door for an automobile of my new design;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a right side elevational view of my new design, the left side elevational view being a mirror image of FIG. 6.
